UNITED STATES PATENT OFFICE.

OSCAR J. KILLIP, OF REDLANDS, CALIFORNIA.

MOTOR-VEHICLE.

SPECIFICATION forming part of Letters Patent No. 789,663, dated May 9, 1905.

Application filed March 3, 1904. Serial No. 196,406.

To all whom it may concern:

Be it known that I, OSCAR J. KILLIP, a citizen of the United States, and a resident of Redlands, in the county of San Bernardino 5 and State of California, have made a certain new and useful Invention in Motor-Vehicles; and I declare the following to be a full, clear, and exact description of the same, such as will enable others skilled in the art to which it applies to make and use the invention, reference being had to the accompanying drawings, and to letters and figures of reference marked thereon, which form a part of this specification.

Figure 1 is a side elevation of the invention as applied. Fig. 2 is a plan view of the same with vehicle partly broken away. Fig. 3 is a detail perspective view. Fig. 4 is a section on the line 4-4, Fig. 3. Fig. 5 is a detail perspective view.

The invention relates to motor-vehicles; and it consists in the novel construction and combinations of devices, as hereinafter set forth.

In the accompanying drawings, illustrating 25 the invention, the letter *a* designates the frame of the machine, which may be supported in any ordinary manner from the axles *b* and *c*.

Over the front axle *b* is supported a motor 30 *c*, adapted to turn the short shaft *d*, which is provided, usually, with a fly-wheel *e* and is connected to the sectional extension-shaft *f* by means of a flexible or knuckle joint *g*. At its rear end this long shaft *f* is connected 35 to the stem *h* of the plane friction-disk *k* by means of another flexible or knuckle joint *m*. The front and rear sections of the shaft *f* are connected by a sleeve-coupling *p*, forming a slip-joint to accommodate the transverse 40 movement of the friction-disk.

The stem *h* of the friction-disk *k* is seated in the bearing of a slide *s*, which plays transversely on the track *t*, which extends cross-wise of the frame, being supported on the 45 braces *v*, which are connected to the reach and the rear axle. In this manner the friction-disk is made adjustable in the plane of its face.

In front of the rear axle is located in bearings 50 of the brace-framing connected to the

reach a transverse shaft *v'*, to the ends of which are secured the drive-wheels *w*, the bearing edges of which are made concave to correspond with the convex tires of the rear wheels *z* of the machine, which are engaged 55 thereby. To the middle of the shaft is rigidly secured the friction gear-wheel *3*, which is designed to be operated by the friction-disk *k*, the plane of which is at right angles to that of the friction-wheel. 60

The controlling-lever is indicated at *4*, and it is provided with connections *5*, whereby the operation of the bearing-slide *s* of the friction-disk *k* is effected, the slide being moved to the right or to the left, as may be desired. 65 This adjustment is readily and easily effected while the vehicle is in motion, as the friction-disk is movable on a flexible or pivot joint connection which is not hampered by the momentum of the vehicle. 70

When the friction-disk is moved so that it is centered on the friction-pulley, the transverse shaft and drive-wheels are not moved and the vehicle remains stationary. When the friction-disk is moved to the right, the 75 motor-shaft turning to the right in the ordinary manner, the drive-wheels will turn the vehicle-wheels for forward motion, the speed being increased as the disk is moved farther from its central position. The reverse movement of the disk to the left causes it to engage the friction-wheel to the right of its center, so that the drive-wheels are turned in the opposite direction, moving the vehicle-wheels backward. As the drive-wheels shown in this 80 construction engage the tires of the vehicle-wheels, all the leverage possible is obtained, and it is designed to use large vehicle-wheels with solid rubber tires in order to economize in power. In order to keep the friction-disk 85 in proper engagement upon the friction-wheel, set-screws are employed the pressure of which may be regulated.

Having described this invention, what I claim, and desire to secure by Letters Patent, 95 is—

1. The combination with the vehicle-wheels, of the motor and jointed motor-shaft, its plane friction-disk, the drive-wheels, their shaft and its rigidly-attached friction-wheel, and means 100

for moving the friction-disk in the plane of its face transversely of said friction-wheel, substantially as specified.

2. The combination with the vehicle-wheels, 5 drive-wheels, their transverse shaft and the friction-wheel rigidly secured to said shaft, of the motor, its jointed extension - shaft, and plane friction-disk, and the transverse bearing-slide of said friction-disk, substantially as 10 specified.

3. The combination with the vehicle-wheels, drive-wheels, their shaft and its rigidly-attached friction-wheel, of the jointed extension motor-shaft, the plane friction-disk of said 15 shaft, its transversely-adjustable bearing-slide, and the controlling-lever thereof, substantially as specified.

4. The combination with the vehicle-wheels, and the jointed extension motor-shaft, of the

drive-wheels, their shaft, and its rigidly-attached friction-wheel, the plane friction-disk attached to the jointed motor-shaft, and means 20 for moving the same transversely of the friction-wheel, substantially as specified.

5. The combination with the vehicle-wheels, 25 the jointed extension motor-shaft, and fly-wheel, of the drive-wheels, their shaft and rigidly-attached friction-wheel, the plane friction-disk attached to the jointed motor-shaft, its bearing-slide, and means for moving said 30 slide, substantially as specified.

In testimony whereof I affix my signature in presence of two witnesses.

OSCAR J. KILLIP.
